Fig. 2

To all whom it may concern:

Be it known that I, Alec Bradley Kirkbride, a subject of the Queen of Great Britain, residing at London, England, have invented a new, original, and ornamental Design for a Printing Machine, of which the following is a specification, reference being had to the accompanying drawing, forming part thereof.

Fig. 1 is a front perspective view of the printing machine, and

Fig. 2 is a rear perspective view thereof.

The opposite side of the printing machine is plain, having no switches or levers.

I claim:

The ornamental design for a printing machine, as shown and described.
